UNITED STATES PATENT OFFICE.

SIRON LONZE REEVES, OF ATLANTA, GEORGIA.

CAR-COUPING.

SPECIFICATION forming part of Letters Patent No. 402,615, dated May 7, 1889.

Application filed February 28, 1889. Serial No. 300,913. (No model.)

To all whom it may concern:

Be it known that I, SIRON LONZE REEVES, a citizen of the United States, residing at Atlanta, in the county of Fulton and State of Georgia, have invented new and useful Improvements in Car-Couplings, of which the following is a specification.

The invention relates to improvements in car-couplings; and it consists in a certain novel construction and combination of parts fully described hereinafter, in connection with the accompanying drawings, and specifically pointed out in the appended claims.

In the drawings, Figure 1 is perspective view of a coupler embodying the improvements. Fig. 2 is a horizontal sectional view thereof. Fig. 3 is a vertical longitudinal sectional view. Fig. 4 is a detail view of the draw-bar.

Referring by letter to the drawings, A designates the draw-head, which is provided with a flared or V-shaped recess, B, in its front end, and vertical shoulders C C are formed on opposite sides of the said recess near the extremity of the draw-head.

D D designate vertical leaves, which are mounted on vertical pivots E E in rear of the said shoulders, the width of each leaf being slightly more than half the width of the mouth of the draw-head, so that both leaves cannot at the same time assume positions across the mouth of the draw-head. Shoulders d d are formed at the top and bottom of the mouth of the draw-head to prevent the said leaves from swinging outward far enough to bring their extreme edges in contact.

Small supporting-blocks F F are arranged in the center or apex of the V-shaped recess in the draw-head, and their outer ends, which are adjacent to the free edges of the swinging leaves, are tapered, as shown. The function of these blocks is to support the end of the link which is within the draw-head, to prevent the same from sliding down out of the proper or horizontal position.

G designates the coupling-link, which is provided at its ends with the tapered arrow-heads g g, having shoulders at their inner ends, which are engaged by the free edges of the leaves. This link will separate the leaves as it enters the recess of the draw-head; but after its shoulders have passed the free edges of the

leaves the latter swing outward and firmly engage the said shoulders.

Springs H H are arranged in rear of the leaves to hold them normally pressed outward against the shoulders d d in position to engage the shoulders of the link.

K designates a draw-bar, which operates in a horizontal perforation, I, near the bottom of the draw-head, and is provided at its front end with a beveled or wedge-shaped head, L, which is arranged in front of the swinging leaves. If this draw-bar is drawn rearwardly, its head is drawn between the free edges of the leaves, thereby separating the latter and enabling the link to be removed from the draw-head. The rear free end of this draw-bar is connected to a crank-shaft, M, which is mounted in suitable bearings in the draw-head, and this crank-shaft is provided at its ends on opposite sides of the draw-head with the crank-arms N N, whereby the said shaft may be rotated to operate the draw-bar.

The operation of this improved coupler will now be readily seen. The link is guided to the free edges of the leaves by the flared sides of the recess and the inclined leaves, the outer sides of the latter being flush with the shoulders C C, and the tapered head of the link separates the adjacent edges of the leaves and passes between them, and when they resume their normal positions the head of the link is engaged. To disengage the link the crank-shaft is rotated, thereby retracting the draw-bar and separating the free edges of the leaves.

Having thus described the invention, I claim—

1. In a car-coupling, the combination, with the draw-head provided with a recess in its front end, of the spring-actuated swinging leaves pivoted therein and inclined rearwardly toward their adjacent edges, and the draw-bar provided with a beveled or wedge-shaped head, which is arranged between the leaves to enable the latter to be separated, substantially as specified.

2. In a car-coupling, the combination, with the draw-head provided with a recess in its front end, of the swinging spring-actuated leaves pivoted therein and inclined rearwardly toward their adjacent edges, the draw-bar provided with a wedge-shaped head which is arranged between the leaves, and the crank-

shaft mounted on the draw-head and connected to the draw-bar, whereby the latter may be drawn rearwardly to separate the leaves, substantially as specified.

5. In a car-coupling, the combination, with the draw-head provided with a flared or V-shaped recess having shoulders C C at its sides and shoulders d d at its top and bottom, of the swinging spring-actuated leaves pivoted in rear of the shoulders C C and normally bearing at their upper and lower edges against the shoulders d d, and the draw-bar provided with a wedge-shaped head arranged between the leaves, substantially as and for the purpose specified.

6. The combination of the draw-head, the

leaves pivoted therein, and the draw-bar mounted in the draw-head and adapted to separate the leaves, as set forth.

7. The combination of the draw-head having the tapered supporting-blocks F, the leaves pivotally mounted in the draw-head, and the draw-bar sliding in the draw-head and adapted to separate the leaves, as set forth.

In testimony that I claim the foregoing as my own I have hereto affixed my signature in presence of two witnesses.

SIRON LONZE REEVES.
